ERNEST POIRIER, OF WATERVILLE, MAINE, ASSIGNOR OF TWENTY-FIVE ONE-HUNDREDTHS TO JOHN W. STOBIE, OF WATERVILLE, MAINE

PAPER MAKING PROCESS AND MACHINE

Application filed September 16, 1931. Serial No. 563,038.

This invention relates to the manufacture of paper and paper articles. It aims to improve both the processes of and also the apparatus for making paper with a view to facilitating the control of the process and more especially to reducing the variations in the thickness or weight of the paper due to variations in the consistency of the paper making stock.

10 The nature of the invention will be readily understood from the following description when read in connection with the accompanying drawings, and the novel features will be particularly pointed out in the appended 15 claims.

In the drawings,

Figure 1 is a perspective view illustrating an apparatus embodying the present invention;

20 Fig. 2 is a plan view of the apparatus shown in Fig. 1;

Fig. 3 is a vertical, sectional view of said apparatus; and

25 Fig. 4 is a horizontal, sectional view through the gates of the apparatus illustrated in the other figures.

The apparatus shown in the drawings comprises a head box 2, this head box being provided with a partition 3 which divides it into 30 two main sections, and with a weir 4 which divides one of these sections into two chambers *a* and *b*. This arrangement is similar to those used heretofore to feed pulp to a paper machine. Obviously any equivalent 35 device may be substituted for it. Paper making stock or pulp is pumped into the chamber *a* through an inlet opening *d*, and the surplus overflows the weir 4 into the chamber *b* where it drains through an outlet *e* and is led back to the supply tank, the 40 weir serving to maintain an approximately constant head in the chamber *a*. A curved pipe 5 leads through the partition 3 and connects the inlet chamber *a* with the discharge 45 chamber *c* so that approximately a constant level of stock is maintained in the latter chamber. In the front wall of the box a discharge outlet 6 is provided through which the stock flows into pipe connections which 50 lead it to the paper making wire or other

apparatus on which the paper is made. A common arrangement is to pump the stock discharged through the outlet 6 through a pulp screen and then to deliver the screened stock directly to the wire of a Fourdrinier 55 machine. The head box also is provided with a gate 8 for adjusting the size or area of the outlet 6, the gate being slidable in guides 9-9 at the front of the box. Any suitable means may be provided for adjusting the 60 gate vertically. As shown, this adjusting means comprises a rod 10 secured to the gate and having a threaded upper end portion projecting through a horizontal bracket 12 and engaged by a nut 13 which rests on the 65 bracket. By turning this nut the gate may be raised or lowered, as desired.

The construction so far described is substantially like that in common use for controlling the flow of pulp or paper stock to the 70 pulp screen or to the wire of a Fourdrinier paper making machine. The wire travels at a substantially constant speed, and if the stock has a uniform consistency and is delivered to the wire at a constant rate, a uniform 75 sheet or web should be produced. As is well understood by those skilled in this art, the paper making stock or pulp consists of a very high percentage of water with a relatively small percentage of solid constituents such 80 as fibre, fillers, and the like, suspended in the water. A very common cause of variations in the thickness or weight of the sheet of paper being made in the machine is the fact that the consistency of the stock changes 85 while the machine is running. As soon as the machine attendant observes that a thicker or thinner web is being produced, he makes proper changes, usually by adjusting the gate 8, to compensate for the variation in the concentration of solid constituents in the stock. The necessity for making such adjustments, 90 however, calls for close attention and a high degree of skill on the part of the machine attendant. The present invention deals particularly with these considerations.

I have found that when the stock becomes thinner, or in other words, the concentration of solid constituents is reduced, the stream of stock flowing through the outlet 6 changes 100

somewhat in shape, the stream becoming somewhat longer and its curve being more gradual. On the other hand, when the stock becomes thicker, or the proportion of solid constituents is greater, the stream shortens and the curve is somewhat sharper.

The present invention makes use of this fact. It utilizes variations in the consistency of the stock to control the rate of delivery of the stock from the head box in such a manner as to maintain an approximately constant rate of delivery of solid constituents, notwithstanding variations in the consistency of the stock. It is contemplated that this control may be effected in a considerable variety of ways, as for example, by changing the head of the stock in the head box 2, or by changing the size of the outlet 6 so that the rate of delivery of the stock, that is, the volume delivered in a unit of time, will be correspondingly changed. The construction shown in the drawings is designed to adjust the size of the discharge outlet 6.

This arrangement comprises a device 15 which, as shown, has the form of an inverted scoop for engaging the stream of stock issuing from the discharge outlet 6 of the head box. This device is pivoted at 16 to a bracket 17 which is secured to the gate 8 for vertical adjustment, as clearly shown in Fig. 1. A supplemental gate 18 is arranged to slide in the guides 9 just in front of the main gate 8 and overlapping this gate. It is connected to the device 15 by a link 19 so that as the part 15 swings up or down, it will adjust the supplemental gate 18 to close the discharge opening 6 more or less, depending upon the position which the stream of pulp flowing through this opening causes the member 15 to take. Inasmuch as the position which the device 15 is caused to assume depends upon the shape or contour of the stream of pulp discharged from the head box, this member will be hereinafter referred to as a "vane".

It will be clear from an inspection of the drawings that the vane will be swung outwardly away from the outlet 6 by its contact with the stream of pulp, and that the farther outwardly it is moved the wider will be the opening 6. If, therefore, the machine is adjusted for making a web of a satisfactory weight or thickness and the stock suddenly becomes thicker, the stream will be shortened, as above described, thus causing the vane 15 to swing inwardly and thereby closing the opening 6 correspondingly. This reduces the volume of stock flowing through the opening in a given unit of time, or in other words, reduces the rate of flow of pulp to the wire. Due to the fact, however, that the stock is thicker or contains a higher concentration of solid constituents, the rate of delivery of such solid constituents to the wire will remain approximately unchanged, notwithstanding the reduced volume of pulp.

Consequently, the thickness or weight of the web being made will remain approximately the same. On the other hand, if the stock should begin to run thinner, the stream would be lengthened, thus opening the gate wider, thereby allowing a greater rate of flow of stock to the wire; but since the stock carries a lower concentration of fibre and other solid constituents, the total quantity of such constituents delivered to the wire in a given unit of time remains approximately unchanged.

In order to permit adjustment of the operative relationship between the supplemental gate 18 and the vane 15, the vane is slotted, as shown at 20, to permit adjustment of the pivot bolt for the link 19 in a direction toward or from the axis 16 on which the vane swings.

A shower pipe, indicated at 21 in Fig. 3, usually is provided to direct a spray on the upper surfaces of the vane to keep it and adjacent parts substantially free from accumulations of fibre.

It has been definitely determined in practice that the arrangement above described substantially improves the evenness or uniformity of the sheet or web of paper being made. The apparatus is entirely automatic in its action, and because of this fact it substantially reduces the care and skill required on the part of the machine attendant. At the same time it can be adjusted readily to suit different thicknesses or weights of paper to be made. The vane follows the contour of the stream of pulp very closely. It has broad surfaces to engage this stream and there is ample power in the flowing stock to operate through the vane in the manner above described.

For many purposes the apparatus above described is entirely satisfactory. It is a common practice, however, to recirculate a considerable part of the "white water" with the new stock flowing to the wire, partly for the purpose of thinning the stock, and more especially for the purpose of recovering part of the fillers, sizing, and other solid constituents of the stock which go through the wire. When this practice is followed it is necessary for the machine tender to adjust the volume of the "white water" which he allows to flow on to the wire in accordance with variations in the consistency of the stock and other operating conditions. In some cases the stock will become "too quick", or, in other words, the water will leave the sheet too quickly, while at other times the stock will tend to run "too slow"; that is, the water will not leave the sheet quickly enough. Either of these conditions ordinarily must be corrected by manual adjustment of the white water or the new stock, or both. I have found that the movements of the vane 15 can be utilized to control the volume of white water as well as

70

of the new stock. The arrangement shown in the drawings is designed for this purpose.

Referring more particularly to Figs. 1 and 3, it will be seen that a second head box 24 is mounted immediately below the upper box 2, and that it is divided by a weir 25 into inlet and overflow chambers *f* and *g*, respectively. The white water is pumped into the chamber *f*, overflows the weir *g*, and the surface is drained away, the weir maintaining an approximately constant head in the chamber *f*. A discharge outlet 26 for the white water leads from the latter chamber. The size of this outlet may be adjusted by means of a gate 27 mounted to slide across the aperture 26 in guides similar to those provided on the upper box. Two links 28 pivoted at their lower ends to the gate 27 are extended upwardly past the opposite sides of the vane 15 and are pivotally connected thereto by bolts which pass through the slots 20.

It will be clear that with this arrangement the swinging movements of the vane 15 will be transmitted to the gate 27 and will close or open this gate more or less, thus automatically changing the volume of white water discharged into the stream of pulp in response to changes in the consistency of said pulp or stock. In the particular arrangement shown the volume of white water is varied inversely with that of the pulp discharged from the upper head box. This is the arrangement more commonly required because if the stock runs "too slow" it will require less white water, and vice versa, the slow stock will lift the vane 15, thus automatically opening the gate 18 somewhat and partially closing the white water gate 27. On the other hand, if the stock tends to run too free, the vane 15 will drop, thus partially closing the auxiliary stock gate 18 and opening the white water gate 27 somewhat wider.

It should perhaps be noted that only a part of the white water going to the wire usually is circulated through the head box 24. If it is desired to reverse the arrangement shown, and to have the gates 18 and 27 work simultaneously in the same direction, this can be done by sliding the gate 27 upwardly into the upper portions of its guides and into such a position that it will work across the upper edge of the opening 26 instead of the lower edge, this adjustment being permitted by the fact that the upper ends of the links 28 have holes punched through them to permit a wide range of vertical adjustment of the links relatively to the vane.

The head box shown in Figs. 2 and 3 also is of novel construction. It will be observed that the pipe 5 which leads the stock from the inlet chamber *a* into the discharge chamber *c* is curved upwardly and that it is of smaller cross-sectional area than the inlet pipe *d*. This means that the flow of stock

into the chamber *c* will be impeded slightly. A gate 30 also is mounted in suitable guides to slide across the intake end of this pipe and is connected with a rod 31 so that the gate can be adjusted to close this intake end more or less. As the consistency of the stock increases, its flow through the pipe 5 into the discharge chamber *c* will be retarded due to this increase in consistency and to the shape and smaller cross-sectional area of the parts through which it must flow into this chamber. Consequently, a slight variation in the level or hydraulic head of stock in the chamber *c* will be produced automatically when substantial changes in consistency of the stock occur.

Preferably the pipe 5 is directed upwardly and is located at the opposite end of the chamber *c* from the discharge outlet 6 so that no "short circuiting" of the stock will occur between the pipe 5 and the outlet.

Preferably, also, an aperture 32 is provided through the partition 3 between the overflow chamber *b* and the discharge chamber *c* closely adjacent to the bottom of the box, this aperture normally being closed by a gate 33 arranged to be operated by a screw 34. This gate arrangement is like that provided in the chamber *a*. It is useful in flushing out the head box in changing from one kind of stock to another.

The lower head box 24 can be used not only to handle the white water but clear water, if desired, or any other liquid which is to be mixed with the pulp flowing through the upper head box.

While I have herein shown and described a preferred embodiment of my invention, it will be understood that the invention may be embodied in other forms without departing from the spirit or scope thereof. Also, that while the paper making surface to which the stock is delivered has herein been referred to chiefly as a "wire", it is immaterial, so far as this invention is concerned, whether this surface is a wire or a paper making surface of some other form. The term "wire", therefore, is herein used in the claims in a generic sense to include other paper making surfaces.

This application is a continuation in part of my pending application Serial No. 459,083, filed June 3, 1930.

Having thus described my invention, what I desire to claim as new is:

1. That improvement in methods of feeding paper stock to a paper making wire which consists in causing variations in the shape of a stream of the stock flowing to the wire to effect such adjustments of the rate of delivery of stock to the wire as to maintain an approximately constant rate of delivery of solid constituents of the stock notwithstanding variations in its consistency.

2. That improvement in methods of feed-

- ing paper stock to a paper making wire which consists in flowing stock from a head box to the paper making wire, and causing changes in the shape of the stream flowing from the 5 head box to so adjust the rate of delivery of stock to the wire as to maintain an approximately constant rate of delivery of solid constituents of the stock notwithstanding variations in its consistency.
- 10 3. That improvement in methods of feeding paper stock to a paper making wire which consists in causing variations in the shape of a stream of the stock flowing to the wire to produce such adjustments of the cross sectional area of said stream as to maintain an approximately constant rate of delivery of solid constituents of the stock in said stream notwithstanding variations in the consistency of said stock.
- 15 4. That improvement in methods of feeding paper stock to a paper making wire which consists in causing variations in the shape of a stream of the stock flowing to the wire to so adjust the rate of delivery of said stock to the wire as to reduce substantially the variations in the delivery of the solid constituents of the stock which otherwise would be caused by variations in the consistency of the stock.
- 20 5. That improvement in methods of feeding paper stock to a paper making wire which consists in causing variations in the shape of a stream of the stock flowing to the wire to so adjust the rate of delivery of said stock to the wire as to reduce substantially the variations in the delivery of the solid constituents of the stock which otherwise would be caused by variations in the consistency of the stock, adding water continuously to said stream, and causing said variations in the shape of 25 said stream to control the amount of water so added.
- 30 6. In an apparatus of the character described, the combination with a head box having a stock delivery outlet through which a stream of stock may flow, of a device for engaging said stream without substantially impeding the flow of the stream, means supporting said device for movement into different positions determined by the shape of 35 said stream, and means under the control of said device for changing the volume of flow of stock from said box in response to changes in the position of said device.
- 40 7. In an apparatus of the character described, the combination with a head box having an outlet for a stream of stock, of a vane for engaging said stream, means supporting said vane to swing in a fixed path into different positions determined by the 45 action thereon of said stream, and means for causing movements of said vane to effect adjustments in the volume of flow of stock from said box to vary the rate of flow inversely with variations in the concentration of the 50 stock.
8. In an apparatus of the character described, the combination with a head box having an outlet for a stream of stock, of a vane for engaging said stream without substantially impeding the flow of said stock, means supporting said vane for movement into different positions by said stream, and a gate for adjusting the size of said outlet, said gate being connected with said vane to cause changes in the position of the vane to adjust 55 said gate.
9. In an apparatus of the character described, the combination with a head box having an outlet for a stream of stock, of a vane for engaging said stream, means supporting 60 said vane for swinging movement in a fixed path due to the action thereon of said stream, a gate for adjusting the size of said outlet, and connections between said vane and said gate for causing changes in the position of 65 said vane to effect adjustments of said gate.
10. In an apparatus of the character described, the combination with a head box having a stock delivery outlet through which a stream of stock may be discharged, of a vane for engaging said stream, a gate for adjusting the size of said outlet, and connections between said gate and said vane for causing outward movements of the vane away from 70 said outlet to increase the size of said outlet, and inward movements of said vane to decrease the size of said outlet.
11. In an apparatus of the character described, the combination with a head box having a stock delivery outlet through which a stream of stock may be discharged, of a vane for engaging said stream, a gate connected with said vane for adjusting the size of said outlet in response to changes in the position of 75 said vane, and connections between said vane and said gate adjustable to change the operative relationship between the vane and the gate.
12. In an apparatus of the character described, the combination with a head box having a stock delivery outlet, a vane for engaging the stream of stock flowing through said outlet, means supporting said vane for swinging movement whereby the position taken by the vane will vary with changes in the shape 80 of said stream, a gate mounted for adjustment to vary the size of said outlet, and connections between said vane and said gate for causing changes in the position of said vane to adjust said gate.
13. In an apparatus of the character described, the combination with a head box having a stock delivery outlet, a vane for engaging the stream of stock flowing through said outlet, means supporting said vane for swinging movement whereby the position taken by the vane will vary with changes in the shape 85 of said stream, a main gate adjustable to vary the area of said outlet, a supplemental gate adjustable independently of said main gate.
14. In an apparatus of the character described, the combination with a head box having a stock delivery outlet, a vane for engaging the stream of stock flowing through said outlet, means supporting said vane for swinging movement whereby the position taken by the vane will vary with changes in the shape 90 of said stream, a main gate adjustable to vary the area of said outlet, a supplemental gate adjustable independently of said main gate.
15. In an apparatus of the character described, the combination with a head box having a stock delivery outlet, a vane for engaging the stream of stock flowing through said outlet, means supporting said vane for swinging movement whereby the position taken by the vane will vary with changes in the shape 95 of said stream, a main gate adjustable to vary the area of said outlet, a supplemental gate adjustable independently of said main gate.
16. In an apparatus of the character described, the combination with a head box having a stock delivery outlet, a vane for engaging the stream of stock flowing through said outlet, means supporting said vane for swinging movement whereby the position taken by the vane will vary with changes in the shape 100 of said stream, a main gate adjustable to vary the area of said outlet, a supplemental gate adjustable independently of said main gate.
17. In an apparatus of the character described, the combination with a head box having a stock delivery outlet, a vane for engaging the stream of stock flowing through said outlet, means supporting said vane for swinging movement whereby the position taken by the vane will vary with changes in the shape 105 of said stream, a main gate adjustable to vary the area of said outlet, a supplemental gate adjustable independently of said main gate.
18. In an apparatus of the character described, the combination with a head box having a stock delivery outlet, a vane for engaging the stream of stock flowing through said outlet, means supporting said vane for swinging movement whereby the position taken by the vane will vary with changes in the shape 110 of said stream, a main gate adjustable to vary the area of said outlet, a supplemental gate adjustable independently of said main gate.
19. In an apparatus of the character described, the combination with a head box having a stock delivery outlet, a vane for engaging the stream of stock flowing through said outlet, means supporting said vane for swinging movement whereby the position taken by the vane will vary with changes in the shape 115 of said stream, a main gate adjustable to vary the area of said outlet, a supplemental gate adjustable independently of said main gate.
20. In an apparatus of the character described, the combination with a head box having a stock delivery outlet, a vane for engaging the stream of stock flowing through said outlet, means supporting said vane for swinging movement whereby the position taken by the vane will vary with changes in the shape 120 of said stream, a main gate adjustable to vary the area of said outlet, a supplemental gate adjustable independently of said main gate.
21. In an apparatus of the character described, the combination with a head box having a stock delivery outlet, a vane for engaging the stream of stock flowing through said outlet, means supporting said vane for swinging movement whereby the position taken by the vane will vary with changes in the shape 125 of said stream, a main gate adjustable to vary the area of said outlet, a supplemental gate adjustable independently of said main gate.
22. In an apparatus of the character described, the combination with a head box having a stock delivery outlet, a vane for engaging the stream of stock flowing through said outlet, means supporting said vane for swinging movement whereby the position taken by the vane will vary with changes in the shape 130 of said stream, a main gate adjustable to vary the area of said outlet, a supplemental gate adjustable independently of said main gate.

to change the area of said outlet, and connections between said vane and said supplemental gate for causing changes in the position of said vane to adjust said supplemental 5 gate.

14. In an apparatus of the character described, the combination with a head box having a stock delivery outlet, a main gate adjustable to vary the area of said outlet, a 10 vane for engaging the stream of stock flowing through said outlet, means for supporting said vane on said main gate for swinging movement about a horizontal axis adjacent to the upper edge of said outlet whereby the 15 position taken by said vane will vary with changes in the shape of said stream, a supplemental gate adjustable independently of said main gate to change the area of said outlet, and connections between said vane and 20 said supplemental gate for causing changes in the position of said vane to adjust said supplemental gate.

15. In an apparatus of the character described, the combination with a head box having a stock delivery outlet, a vane for engaging the stream of stock flowing through said outlet, means supporting said vane for movement into different positions determined by the action thereon of said stream, means under the control of said vane for changing the volume of flow of stock from said box in response to changes in the position of said vane, means operative to supply water continuously to said stream, and additional 30 means under the control of said vane for governing the quantity of water so supplied.

16. In an apparatus of the character described, the combination with a head box having a stock delivery outlet, a vane for engaging the stream of stock flowing through said outlet, means supporting said vane for movement into different positions determined by the action thereon of said stream, means operable to deliver water continuously to 45 said stream, a device adjustable to change the rate of delivery of said water, and means connecting said device with said vane to cause the vane to adjust said device automatically in response to changes in the position of said 50 vane.

17. In an apparatus of the character described, the combination with a head box having a stock delivery outlet, a vane for engaging the stream of stock flowing through said 55 outlet, means supporting said vane for swinging movement whereby the position taken by the vane will vary with changes in the shape of said stream, a gate adjustable to vary the size of said outlet, means for adding water continuously to said stream, a device adjustable to control the amount of water so added, and means connecting said vane with said 60 gate and said device to cause changes in the position of said vane to adjust both said gate and said device.

18. In an apparatus of the character described, the combination with a head box having a stock delivery outlet, a vane for engaging the stream of stock flowing through said outlet, means supporting said vane for swinging movement whereby the position taken by the vane will vary with changes in the shape of said stream, a gate adjustable to vary the size of said outlet, means for adding water continuously to said stream, a device adjustable to control the amount of water so added, and connections between said vane and said gate and between said vane and said device for causing changes in the position of said vane to adjust both said gate and said device, said connections being adjustable to change the operative relationship of said vane to said gate and said device. 70

19. In an apparatus of the character described, the combination with a head box having a stock delivery outlet, a vane for engaging the stream of stock flowing through said outlet, means supporting said vane for swinging movement whereby the position taken by the vane will vary with changes in the shape of said stream, a gate mounted for adjustment to vary the size of said outlet, connections between said vane and said gate for causing changes in the position of said vane to adjust said gate, a second head box located below the first head box and having a discharge outlet, a gate for adjusting the size of the latter outlet, and connections between the last mentioned gate and said vane for causing the changes in the position of said vane to adjust last mentioned gate. 80

20. In an apparatus of the character described, the combination of a head box having a partition dividing it into two main sections, a weir dividing one of said sections into inlet and overflow chambers, respectively, the other section forming a discharge chamber, means for conducting stock into said inlet chamber, a curved pipe extending through said partition for conducting stock from said inlet chamber into said discharge chamber, and a discharge outlet leading from said discharge chamber, the end of said pipe in said discharge chamber being directed away from said discharge outlet. 90

21. In an apparatus of the character described, the combination of a head box having a partition dividing it into two main sections, a weir dividing one of said sections into inlet and overflow chambers, respectively, the other section forming a discharge chamber, means for conducting stock into said inlet chamber, an aperture extending through said partition for conducting stock from said inlet chamber into said discharge chamber, and a discharge outlet leading from said discharge chamber at a point remote from said aperture. 100

22. In an apparatus of the character described, the combination of a head box hav- 115

ing a partition dividing it into two main sections, a weir dividing one of said sections into inlet and overflow chambers, respectively, the other section forming a discharge chamber, means for conducting stock into said inlet chamber, apertures through said partition providing communication between said discharge chamber and said inlet and overflow chambers, and gates for closing said

10 apertures.

23. In an apparatus of the character described, the combination of a head box having a partition dividing it into inlet and discharge compartments, means for conducting stock into said inlet compartment, a weir in the latter compartment over which the surplus stock flows, means for conducting stock from said inlet compartment to said discharge compartment but shaped and proportioned to automatically vary the rate of flow of the stock into said discharge compartment in response to variations in the consistency of the stock, a discharge outlet leading from said discharge compartment, and means for controlling the rate of flow of the stock through said discharge outlet and for automatically varying said rate inversely with variations in the concentration of the stock.

24. In an apparatus of the character described, the combination of a head box having a partition dividing it into inlet and discharge compartments, means for conducting stock into said inlet compartment, a weir in the latter compartment over which the surplus stock flows, means for conducting stock from said inlet compartment to said discharge compartment but shaped and proportioned to automatically vary the rate of flow of the stock into said discharge compartment in response to variations in the consistency of the stock, a discharge outlet leading from said discharge compartment, a vane for engaging the stream of stock discharged from said discharge outlet, means supporting said vane for movement into different positions determined by the contour of said stream, and means for causing the movements of said vane to effect adjustments in the volume of flow of stock through said outlet to vary the rate of said flow inversely with variations in the concentration of the stock.

25. In an apparatus of the character described, the combination of a head box having a partition dividing it into inlet and discharge compartments, means for conducting stock into said inlet compartment, a weir in the latter compartment over which the surplus stock flows, a curved pipe for conducting stock from said inlet compartment into said discharge compartment, said pipe being so shaped and proportioned as to vary the rate of flow of stock into said discharge compartment automatically in response to variations in the consistency of the stock, a discharge outlet leading from said discharge

compartment, a device for engaging the stream of stock discharged through said discharge outlet without substantially impeding the flow of the stream, means supporting said device for movement into different positions determined by the shape of said stream, and means under the control of said device for varying the volume of stock discharged through said outlet automatically in response to changes in the position of said device.
